Atty's.

UNITED STATES PATENT OFFICE.

GUNNAR O. LILJEGREN, OF ST. LOUIS, MISSOURI.

AUTOMATIC FIRE-EXTINGUISHER.

1,123,329.

Specification of Letters Patent.

Patented Jan. 5, 1915.

Application filed January 12, 1914. Serial No. 811,572.

To all whom it may concern:

Be it known that I, GUNNAR O. LILJEGREN, a citizen of the United States, residing in the city of St. Louis and State of Missouri, have invented a new and useful Automatic Fire-Extinguisher, of which the following is a specification.

This invention relates to improvements in automatic fire extinguishers of the type which are employed in buildings for the purpose of automatically admitting streams of water in event of a conflagration within the building containing the system.

An object of the invention is to provide an automatic sprinkler head comprising a head adapted to be removably connected to a distributing pipe, and a yoke or frame formed in connection with the head, in combination with a strut composed of two members interposed between a closure on the head and a binding device mounted in the yoke or frame.

Another object is to provide a sprinkler head of the class mentioned with an improved strut for holding the closure in position on the head, and comprising two members one of which abuts against the closure, and the other of which engages a retaining member on the yoke, said two members being provided with a single point of contact for receiving the pressure of the closure, and being retained in position by fusible solder.

A further object of the invention is to provide an improved strut for automatic sprinkler heads comprising two members having a single point of contact for receiving the pressure, and fusible solder for holding said two members together.

Other objects will appear from the following detail description, reference being made to the accompanying drawings in which—

Figure 1 is a side elevation of a sprinkler head embodying my invention. Fig. 2 is a longitudinal sectional view. Fig. 3 is a cross-sectional view on the line 3—3 of Fig. 1.

The head 1 is exteriorly threaded so that it may readily be connected to one of the distributing pipes of the extinguisher system in the usual manner. The yoke 2 is formed in connection with the head 1, and supports in its outer end a pressure adjusting screw 3. The head 1 is closed by a closure 4 which may seat against an elastic washer or gasket 5 pressing against the

outer end of the head 1. A compression plate 6 is seated against the outer surface of the closure 4, and is provided with a peripheral flange 7 which prevents said plate 60 from accidental displacement.

The strut, which is interposed between the closure and the yoke for holding the closure in position under normal conditions, consists of two coöperating members. The outer member 8 is provided with an enlarged portion 9 at its outer extremity and with a concave recess formed in said enlarged portion for receiving the end of the adjusting screw 3. The companion member 70 is angular in side elevation, that is with reference to the plane of projection, and consists of a portion 11 having one side or face at an angle with respect to a line through the axis of the closure and through 75 the screw 3. The obliquely disposed surface is arranged to be held flat against the side of the member 8 which is also disposed at an oblique angle with respect to said axial line. Said companion member also includes 80 a portion 12 arranged to press against the compression plate 6 to hold the closure in position on the head. The point of union of the portions 11 and 12 is extended to provide a shoulder having a groove 13 extending from side to side thereof, said groove being adapted to receive and constitute a bearing for the rounded end 14 of the member 8. Thus, the pressure from within the 85 distributing pipe is transmitted through the portion 12 of the inner compression member to the inner end of the outer member 8 laterally with respect to the axial line through the closure. The only point of bearing on which the force or pressure is transmitted 90 from the member 11—12 to the outer member is within the groove 13 which is lateral from the points of bearing at the ends of the two members.

When the bonding elements, by which the 100 two members are united, become fusible or broken the pressure from within the distributing pipe causes the member 11—12 to turn on the end 14 of the outer member, while the outer end of the oblique portion 105 11 moves away or separates from the member 8 against which it had been held.

It is an important feature of the device that the two compression members shall be angularly disposed as illustrated in Fig. 2. 110 Because of this angular arrangement of the two parts of the strut the pressure from

within the distributing pipe will immediately separate and force said two members out of position when the fusible solder is subjected to the degree of heat at which 5 said solder fuses.

The member 8 and the portion 11 of the coöperating member are provided with matching or registering holes which are enlarged at their outer ends. The holes are 10 filled with fusible solder as indicated at 15, and the enlargement of said holes in the outer face of the two members of the strut are also filled with solder to form the heads 16. Thus, the two members of the strut are 15 firmly held together by bonding elements comprising bodies of fusible solder passing through holes in said members, and provided with enlargements to engage the outer surfaces of said members to prevent separation. 20 As previously mentioned and as illustrated in Fig. 2 the end 14 of the member 8 is in the form of a rounded or beveled shoulder adapted to turn upon the shoulder 13 by force of the pressure within the distributing 25 pipe when the bonding elements of the strut are broken. The space between the beveled surface of the end of the member 8 and the shoulder 13 is filled with a body of fusible solder 17, which coöperates with the bonding 30 elements 15 to hold the two members of the strut in assembled relation. The solder 17 also constitutes a hermetic seal to protect the abutting portions of the strut members from corrosion, so that the dimensions of 35 the two members will not become altered because of corrosion, or other agents.

The outer end 18 of the part 11 is also rounded or beveled but, as previously explained, terminates short of the solder 40 formed by the enlargement 9 and so does not abut against or contact with said shoulder. This arrangement leaves the two members of the strut free to turn upon their single point of contact formed by the 45 shoulder 13 of the part 12 and the end 14 of the part 8, when the bonding elements become broken or released. The space between the end 18 of the part 11 and the shoulder formed by the enlargement 9 is 50 filled with a quantity of fusible solder 19 which coöperates with the remaining bonding elements to hold the members of the strut assembled until all of said bonding elements are released by the heat of the 55 flagration. The member 8 and the coöperating portion 11 are provided with matching beveled surfaces, which form substantially V-shaped grooves in the strut composed of the two members. The spaces or 60 grooves thus formed are filled with a quantity of fusible solder 20 which are united with the bodies of solder 17 and 19 at the outer edges of the latter to protect all contacting surfaces of the two members of the 65 strut from corrosion.

The distributor or deflector 21 is retained permanently in position by the binding screw 3 so that when the sprinkler head is opened the stream of water will strike the distributor or deflector 21 and be spread 70 and distributed over a large area.

The parts are assembled as shown and described and the sprinkler head is connected to the distributing pipe in the usual manner. In case of a fire the bonding elements which 75 hold the two members of the strut together become fused and broken so that all of the pressure of the water is imparted directly from the portion 12 of one of the strut members to the rounded pivotal portion 14 of the 80 other strut member. Since the point of contact 13—14 is angularly or laterally disposed with respect to a line through the end of the screw 3 and the contact point 22 the two members of the strut will be thrown 85 aside by the pressure of the water. The stream of water passing from the pipe through the sprinkler head strikes the distributor or deflector 21 and is thereby distributed or scattered over a considerable 90 area for the purpose of extinguishing the fire.

It will be understood that there may be alterations and modifications within equivalent limits, and that I do not restrict myself to specific features or details of construction. 95

What I claim and desire to secure by Letters Patent is:

1. In a sprinkler head, the combination 100 with a yoke, a screw mounted in said yoke and a closure, of a strut comprising an inner member bearing against said closure and being angular in projection, a flat face formed on the outer portion of said member 105 obliquely with respect to an axial line through said closure and through said screw, a bearing on said member between said oblique face and said line, a second strut member 110 against the oblique face of said first strut member and bearing at its inner end against said bearing between said oblique face and said axial line, an enlarged portion 115 at the outer end of said second strut member bearing against said screw, and fusible bonding material interposed between the adjacent ends of said members and extending along the edges of the overlapping portions thereof, substantially as described.

2. In a device of the character described, 120 the combination with a closure, a yoke and an adjusting screw in the outer end of said yoke in axial alinement with said closure, of a strut member bearing against said closure, a surface on said strut member at an angle 125 with respect to a line through the axis of said screw and said closure, a bearing on said member between said surface and said line, a second member against said surface and bearing at its inner end against said 130

bearing between said surface and said axial line, an enlarged portion at the outer end of said second member bearing against said screw and being out of contact with said first-named strut member, matching beveled surfaces forming grooves at the side edges of said members, bonding material in said grooves uniting the side edges of said members, and bonding elements passing through said members, substantially as described.

3. In a device of the character described, the combination with a closure, yoke and a screw mounted in said yoke in axial alignment with said closure, of a strut mounted between said screw and said closure and composed of a strut member bearing against said closure, a surface on said strut member

at an angle with respect to a line through the axis of said screw and said closure, a bearing formed between said surface and said line, a second strut member engaging said screw and said bearing, fusible bonding elements passing through said members, and fusible bonding material at the inner end of said second strut member and at the outer end of said first mentioned strut member, substantially as described.

In witness whereof, I have signed this specification in the presence of two subscribing witnesses.

GUNNAR O. LILJEGREN.
